A. B. Willard.

UNITED STATES PATENT OFFICE.

ANDERSON B. COSBY, OF RICHMOND, VIRGINIA.

TOBACCO-WRINGING MACHINE.

SPECIFICATION forming part of Letters Patent No. 501,328, dated July 11, 1893.

Application filed May 16, 1892. Serial No. 433,133. (No model.)

To all whom it may concern:

Be it known that I, ANDERSON B. COSBY, a citizen of the United States, residing at Richmond, in the county of Henrico and State of Virginia, have invented certain new and useful Improvements in Tobacco-Wringing Machines; and I do hereby declare the following to be a full, clear, and exact description of the invention, such as will enable others skilled in the art to which it appertains to make and use the same.

My invention has relation to machines for wringing or pressing substances for the purpose of extracting the moisture contained therein, and is more especially designed for operating upon tobacco whether in leaves, sheets or layers, whereby the same is dried quickly, and among the objects in view, are to provide a machine of the character described in which the upper bearing or squeezing roll may be uniformly adjusted toward and from the lower roll; also, to provide means whereby the rolls may be driven positively and without undue strain upon the bearings or the driving belt.

Other objects and advantages of the invention will appear from the following description when taken in connection with the accompanying drawings.

The invention consists in the construction, arrangement and combination of parts, all as hereinafter fully described, illustrated in the accompanying drawings and pointed out in appended claims.

In the drawings:—Figure 1 is a front elevation of my improved machine. Fig. 2 is a side view thereof. Fig. 3 is a vertical section through the oiling devices and a journal-box. Fig. 4 is a side view showing the arrangement of the pressure indicating scale.

A indicates a suitably constructed supporting frame having a trough B for receiving the liquid squeezed from the material. Beneath said trough and journaled in bearings in the sides of the frame is a driving shaft C which carries a fast pulley D and a loose pulley E intermediate the sides of the frame. I prefer to make the loose pulley slightly less in diameter than the fast pulley so that when the driving belt is shifted upon said loose pulley there will be little or no strain upon said belt.

Upon one of the projecting ends of the shaft C is mounted a fly-wheel F and upon the opposite end is mounted a pinion G which gears with a large gear wheel H mounted upon one end of a shaft I which passes transversely of the machine above the trough and has its bearings in journal boxes supported in the sides of the frame. Upon the opposite end of the shaft I is mounted a pinion K which gears with a similar pinion K' mounted upon one end of a shaft L which also extends transversely of the machine directly above the shaft I and journaled in journal-boxes M supported in the sides of the frame.

Mounted upon the shafts I, L, are the squeezing or pressure rolls N, O, respectively, which may be of any desired or suitable material, and of a length to extend nearly the width of the trough. Upon the shaft I beyond the outer edges of the roll are mounted two flanges P of a diameter sufficient to prevent any moisture expressed from the material from splashing or being thrown upon the gearing of the machine, and causes said liquid to fall into the trough.

The rolls N, O, may be of any suitable diameter and in order that the upper roll may be adjusted toward and from the lower roll when this may be found necessary or desirable I provide the following means:—Q indicates a transversely-arranged shaft which has bearings in ears q, loosely mounted upon the upper ends of vertically-arranged screw-shafts R. The latter have mounted thereupon below the bearing ears q, bevel gear-wheels S which gear with like wheels T mounted on the shaft Q. The latter is provided at one end with an operating handle U for turning the same. The lower ends of the screw-shafts are provided with heads Q' which engage beneath caps Q² screwed upon a threaded extension Q³ of the journal-box M. Q⁴ indicates a plate adapted to slide within the extension Q³ and provided with a socket q⁴ to receive the head of the screw-shaft. Beneath the plate Q⁴ is arranged a coiled spring Q⁵ which is adapted to be compressed by the raising of the journal-box when there is an excess of material passing between the rolls. When the shaft Q is revolved in one direction the shafts R by engaging beneath the caps Q² of the journal-boxes will cause the latter to be

- raised, and when the shaft Q is revolved in the opposite direction the shafts R will be lowered thus permitting the journal-boxes to lower also and consequently bring the rolls 5 nearer together. Thus both ends of roll O will be raised or lowered a corresponding distance so that the roll O will exert a corresponding pressure along its entire length upon the material treated.
- 10 For the purpose of locking the roll at any desired adjustment I provide nuts V loosely mounted upon the screw shafts R said nuts being provided with levers v.
- Upon the upper ends of the sides of the 15 frame or trough are secured bowed springs W. When the roll O has been adjusted to the desired position relatively to the roll N the levers v, are turned until they bear tightly upon the top of the sides of the trough thus 20 wedging or binding the threads of the screw shafts and preventing further rotation of the latter. By turning the levers v, in the opposite direction the nuts of the levers will release the threads of the shafts and the latter 25 may then be rotated. By placing the levers v, upon the bowed springs, said levers and their nuts will not rotate along with the shafts.
- For the purpose of lubricating the journals 30 of the rolls without permitting the lubricant to get access between the journal-boxes and their bearings I provide tubes X which pass downwardly and screw into the said boxes and communicate with shallow grooves x provided within the boxes as shown, said tubes 35 X being provided at their upper ends with cups Y containing lubricant.
- For the purpose of indicating the degree of 40 adjustment of the roll O and therefore the amount of pressure exerted by the same, I provide a suitable scale-plate Z divided into inches and fractions thereof, said scale-plate being secured to the gib Z' at the side of one of the journal-boxes or in close proximity thereto.
- 45 A suitable belt-shifter Z² is provided for shifting the driving belt from the fast to the loose pulley and vice versa.
- For compensating for wear between the 50 journal-boxes and their bearings suitable gibs such as Z' may be used, as shown in the drawings, adapted to be secured by means of set screws between the journal boxes and the main frame.
- 55 It will be seen that by my arrangement of gearing the rolls are rotated in unison in opposite directions to cause the material to be fed through said rolls and be subjected to the required pressure, and that said rolls are driven positively by means of the gear-wheels 60 whereby the roll bearings are not subjected to a downwardly or upwardly pulling strain which is the case in ordinary machines where the rolls are driven by belt and pulley. At the same time much greater power is brought 65 to bear upon the material.

The advantages of my machine will be readily seen from the foregoing description when taken in connection with the accompanying drawings.

What I claim, and desire to secure by Letters Patent, is—

1. In a machine of the character described, the combination of a suitable supporting frame, the lower roll revolvably mounted in said frame, the upper roll also revolvably mounted in the frame, vertical screw-shafts mounted in the frame and adapted to work in the journal-boxes of the upper roll, gear wheels mounted upon the said screw-shafts near their upper ends, bearings carried by the said screw-shafts 80 above the gear-wheels, a horizontal shaft revolvably mounted in said bearings, gear-wheels mounted upon said shaft and meshing with the gear-wheels on the screw-shafts, nuts mounted upon the screw-shafts and provided 85 with levers to effect the rotation of the nuts and cause them to bind upon the upper edges of the frame, and bowed springs carried by said frame and upon which springs said levers are adapted to bear, all arranged for co- 90 operation substantially as described.

2. In a machine of the character described, the combination with a lower roll, of an upper roll mounted in journal-boxes, the latter being provided with the tubular screw-threaded 95 extensions, and means for adjusting the upper roll uniformly comprising screw-shafts provided with heads at their lower ends caps screwed upon the threaded extensions of the journal-boxes and beneath which caps said 100 heads engage, gear wheels mounted upon the upper ends of the shafts, and an operating shaft provided with gear wheels meshing with the gear wheels upon the screw-shafts, and an operating handle upon one end of said operating shaft, as and for the purpose specified.

3. In a machine of the character described, the combination with the lower roll, of an upper roll mounted in journal-boxes, the latter being provided with the tubular screw-threaded extensions, and means for adjusting the upper roll uniformly comprising screw-shafts having heads at their lower ends, caps 110 screwed upon the extensions of the journal-boxes and beneath which caps said heads engage, gear wheels mounted upon the upper ends of the shafts, and an operating shaft 115 provided with gear wheels meshing with the gear wheels upon the screw-shafts, a plate slidingly mounted within the extensions of 120 the journal-boxes, and springs arranged within the latter and bearing upon said plates, as and for the purpose specified.

In testimony whereof I affix my signature in presence of two witnesses.

ANDERSON B. COSBY.
